United States Patent Office

Des. 182,153
Patented Feb. 25, 1958

182,153

MICROFILM CAMERA

Harold Adler, Lincoln, Mass.

Application May 15, 1957, Serial No. 46,177

Term of patent 14 years

(Cl. D61—1)

Fig. 1

Fig. 2

Fig. 1 is a perspective view of a microfilm camera, showing my new design; and

Fig. 2 is a perspective view showing the opposite side.

The rear not shown is conventional.

I claim:

The ornamental design for a microfilm camera, substantially as shown and described.
